PIPE LINE CLEANING METHOD

John E. Loeffler and Obert L. Nordin, Houston, Tex., assignors to Thornhill-Craver Company, Inc., Houston, Tex., a corporation of Texas

Application January 13, 1954, Serial No. 403,712

2 Claims. (Cl. 210—16)

This invention relates to new and useful improvements in pipe line cleaning method, and particularly to methods and apparatus for removing foreign particles from petroleum liquids flowing in a pipe line.

One of the most serious problems in the transportation of fluids, such as petroleum liquids through pipe lines, has been the internal corrosion of such pipe lines. In recent years, the problem of corrosion in pipe lines has been accentuated by the increased distances which petroleum fluids are transported. Under the present practice, the petroleum fluids are transported from the petroleum fields to the refineries and then from the refineries to the ultimate consumers who in many instances are thousands of miles from the petroleum fields. Due to the miles of pipe line thus required, it has become increasingly difficult to prevent corrosion in pipe lines.

The corrosion of the pipe lines presents a two-fold problem, namely, in the corrosion of the pipe itself, and also in the corrosion products, which are largely iron compounds or particles, which occur in the pipe lines and thus contaminate the petroleum fluids delivered to the ultimate consumers. These corrosion products may enter the petroleum liquid at the storage tanks or other equipment at the refinery or may come from a section of corroded pipe in the pipe line, but in any event, regardless of their source, it is known that they are largely responsible for the initiation of corrosion in the pipe line during the transportation of the fluids therethrough. These iron particles attach themselves to the pipe line and form a nucleus for a corrosion spot. Once such a corrosion spot is formed, the corrosion then proceeds at a fairly rapid rate.

In order to remove corrosion products, dirt and similar foreign particles from a pipe line, it has been the practice in the past to run mechanical scraper units through the pipe line for various intervals of the pipe length. Such mechanical scrapers are intended to remove the corrosion products in a pipe line, but they are expensive and also are difficult to handle in use. Furthermore, the removal of the corrosion products in the pipe line by such scraper units generally results in a release of the corrosion products without entirely removing same so that they are subsequently picked up and mixed with the petroleum liquids passing through the pipe.

Another factor which enters into the problem of the removal of corrosion products and other foreign particles from liquids in a pipe line or other liquid conductor is that said products or particles are generally of a size less than 40 microns, and in many instances are only 1 micron or less in size. Particles of such small size are not removable from liquids by the known filter screens or strainers, and so far as is known, no process has been heretofore provided for the removal of particles of a size less than 40 microns while utilizing the usual filter screens or strainers.

It is, therefore, one object of this invention to provide an improved method and apparatus for removing foreign particles, and particularly corrosion products, from fluids

2

such as petroleum fluids flowing through a pipe line or other fluid conductor.

It is an important object of this invention to provide a method and apparatus for removing from a liquid foreign particles, such as corrosion products and dirt of such a size that they cannot ordinarily be removed from the liquid by the known filter screens or strainers, by inserting into the liquid a material capable of attaching to said particles to form an increased particle size capable of being subsequently removed from the liquid by said known screens or strainers.

Another object of this invention is to provide a method and apparatus for removing foreign particles such as corrosion products from fluids flowing in a pipe line, by the continuous injection of a filter material into the pipe line in quantities varied in accordance with the amount of the foreign particles in the fluid to be removed, whereby the fluid can be rendered free or substantially free from such foreign particles.

Still another object of this invention is to provide a method and apparatus for removing foreign particles in a pipe line having a fluid flowing therethrough, by the injection into the pipe line at a point of flow of the fluid of a material capable of attaching to said foreign particles, such as diatomaceous earth, carbon black, and activated alumina, and after the fluid and said material have traveled a predetermined distance, then to filter said material and foreign particles adhering thereto from the fluid with a filter screen or strainer, whereby a clean fluid is delivered downstream in the pipe line.

A further object of this invention is to provide a method and apparatus for removing foreign particles from a fluid, such as petroleum liquids, by first precoating a strainer with a predetermined quantity of material capable of adhering to said foreign particles and thereafter injecting another quantity of said material upstream from the strainer so that the foreign particles become associated with said material as it flows downstream, the other quantity of said material and the foreign particles attached thereto being removed by passing the fluid through the precoated strainer, whereby a porous layer of said material and said foreign particles is formed on the precoated screen to thereby assure filtering action over an extended period of time without materially reducing the quantity of flow or requiring a material increase in pressure to obtain a constant flow through the strainer and the layers formed thereon.

The construction designed to carry out the invention will be hereinafter described together with other features thereof.

The invention will be more readily understood from a reading of the following specification and by reference to the accompanying drawings forming a part thereof, wherein an example of the invention is shown, and wherein:

Figure 1 is a diagrammatic view of the usual pipe line arrangement wherein this invention is utilized.

Figure 2 is an elevation of the preferred apparatus of this invention for injecting a particle-attaching material into a liquid flowing in a pipe line.

In the drawings, the numeral 10 designates the pipe line through which fluids such as petroleum fluids are normally conducted from the refinery or petroleum supply 11 for distribution to the ultimate consumer (Figure 1). This pipe line 10 for the transportation of the fluids may extend for thousands of miles and it will have associated therewith at various intervals of about 35 to 50 miles stations or substations 12 and terminals 14 which are adapted to perform necessary operations in the transportation of the fluids through the pipe line 10 and in the delivery of the fluids to the consumer. Thus, such great lengths of pipe line are used today in the transportation

of petroleum fluids that the problems of preventing or retarding corrosion in such lines, and the delivery of fluids free from corrosion products, as well as other foreign particles including color-forming particles, have become of paramount importance.

Briefly, the method of this invention involves the injection into a fluid of a material or agent which is capable of attaching to foreign particles such as corrosion products in the fluid as the fluid is flowing in a pipe line to thereby enable the removal of such particles or products from the fluids. Thus, the foreign particles are adhered to the particle-attaching material while the fluid is flowing and prior to the removal of the particles and material by a strainer so that units of combined foreign particle and particle-attaching material contact the strainer. Such combined units form layers on a strainer stream which are extremely porous whereby filtration through the strainer can be continued at a substantially constant rate without materially increasing the pressure differential across the layers, even though the layers build up to a considerable thickness. Also, such combined particle and material units are considerably larger in size than the separate particles or material so that effective filtering can be obtained with a strainer screen instead of conventional filter cloth type filters.

Insofar as the apparatus of this invention is concerned, it briefly includes a mixing chamber 23 wherein the particle-attaching material is mixed with a portion of the fluid fed thereto from the pipe line 10 through by-pass inlet pipe 20. The particle-attaching material is thus placed in a fluid condition without diverting the main fluid flowing in the pipe line 10. The material is fed into the mixing chamber 23 from hopper 30 in amounts which are varied in accordance with the amount of foreign particles detected by the detector means 40. The by-passed fluid with the dissolved material therein is returned from the mixing chamber 23 to the pipe line 10 through the return pipe 35, with pump 34 preferably being utilized for the return feeding. The particle-attaching material then flows through a section of the pipe line 10 directly to a strainer and during that flow in the pipe line and prior to reaching the strainer, the particle-attaching material adheres or attaches to the foreign particle in the fluid to form the combined units of particle and material.

The invention is particularly concerned with the removal of foreign particles from flowing liquids, wherein the particles are of such a small size that they cannot be removed by known strainers or screens, and generally it may be stated, that particles of a size less than 40 microns would be the main concern of this invention. The particular foreign particles removed from liquids by the method of this invention may vary, but in the treating of petroleum fluids by the method of this invention, the most common foreign particles are corrosion products, dirt and color-forming matter. Various types of materials or agents are suitable in this invention, the main requirement being that they are capable of attaching or adhering to the foreign particles in the liquid. Throughout this specification and the claims, the term "particle-attaching material" is used to define the suitable materials, examples of which include diatomaceous earth, carbon black and activated alumina. The term, particle-attaching material, is used because it is believed that an adsorption or an attraction between the relatively small particles actually occurs by reason of a charge on the particles or otherwise, although the invention is not to be limited by such theory. It should also be pointed out that for obtaining the most effective results, the particle-attaching material should be substantially the same size as the foreign particles.

The particle-attaching material or agent is introduced into the pipe line or fluid conductor 10 at various points along the length thereof such as indicated by the arrows at X in Figure 1 or at some point of the pipe line within a terminal or station area. The particle-attaching ma-

terial with the foreign particles attached thereto is removed by passing the fluid through one or more strainer units 15 (Figures 6 and 7) located at each of the terminals and stations just ahead of equipment to be protected such as the metering and delivery equipment to be protected usually found at pipe line terminals 14 or stations 12. The strainers 15 which are used may be of numerous types, but the one illustrated in Figures 6 and 7 is of the type disclosed in co-pending U. S. patent applications Serial Nos. 131,017 (filed December 3, 1949) now Patent 2,658,622 and 223,745 (filed April 30, 1951) now Patent 2,670,658 and it will be described in detail hereinafter.

The preferred form of apparatus for injecting the filter material or agent into the pipe line 10 is illustrated in Figure 2. The injector apparatus includes an inlet pipe 20 which is connected to the pipe line 10 for admitting all or a portion of the fluid passing through the pipe line 10 as well as the foreign particles such as corrosion products which may be present in the fluid. A control valve 21 is provided in the inlet line 20 for controlling the inlet of the fluid from the pipe line 10 to the apparatus and for closing off such flow in the instances where the injection apparatus is not to be used. The fluid from the pipe line 10 flows through the inlet pipe 20 and is ultimately discharged into a mixing tank 23 through a pair of oppositely and tangentially disposed mixing inlet pipes 24 (Figure 5). The level of the fluid in the mixing tank 23 is controlled by a float 26 which is connected to a regulating valve 27 through suitable linkage 28. When the level of the fluid in the mixing tank 23 reaches a predetermined level, the float 26 actuates the valve 27 to move same toward a closed position and further inlet of fluid from the pipe line 10 through the inlet pipe 20 is reduced gradually until the liquid level in the tank 23 begins to recede, at which time the valve 27 is gradually opened. Ordinarily, the float 26 will not be actuated to completely close the valve 27, but the float 26 and valve 27 serve as a safety device in rare instances to prevent overflow of fluid in the tank 23.

The particle-attaching material, is a powdered form which is generally made up of granules of a size less than 40 microns, is initially placed in a hopper 30 from which the material is fed into the mixing tank 23 by a feeding device 31. The feeding device 31 may be any conventional powder or granule feeding mechanism which is capable of continuously feeding desired quantities of powdered or granular material in accordance with predetermined settings of the device. The particle-attaching material is fed into the mixing chamber 23 simultaneously with the feeding of the petroleum liquid or other fluid into the chamber 23 so that the filter material and the liquid are thoroughly mixed in the mixing chamber 23. The admixed particle-attaching material and the liquid in the mixing chamber 23 are carried through a return line or pipe 33 by means of a suitable pump 34 to a return outlet 35 connected to the pipe line 10 at a point downstream from the inlet pipe 20. A check valve 36 may be provided to prevent backflow of the fluid in the pipe line into the pump 34 and a control valve 37 may also be provided to stop or regulate return flow to the pipe line 10. Thus, with the apparatus of Figure 2, it is possible to continuously inject particle-attaching material into the pipe line and to properly mix such material with the fluid of the pipe line prior to its injection into the pipe line. In the usual case, it is desirable to vary the amount of the particle-attaching material which is injected into the pipe line 10 in accordance with the amount of foreign particles in the portion of the fluid being treated, and this can be accomplished by an electrical pickup indicator 40 of conventional construction which is capable of responding to the amount of foreign particles present in the fluid passing thereby. Electrical wires 41 from the pickup device 40 are in an electrical system with an electrical responding device 42 of known construction which is operated only when the amount of foreign particles in the

fluid passing thereby changes; the operation of such device 42 causes a change in the rate of feed of the particle-forming material by the feed device which corresponds with the change in the amount of foreign particles in the fluid, as will be explained.

In carrying out the steps of the method of this invention, the particle-forming material is injected into the pipe line 10 by the apparatus shown in Figure 2.

As stated above, although this invention is not limited to the removal of any particular foreign particles in a fluid, it is particularly suitable for the removal of iron and iron compounds, such as the iron oxides, and/or coloring matter in the form of particles, gel and the like, from petroleum fluids. Iron oxides and iron compounds are particularly undesirable in pipe lines since they initiate corrosion therein by attaching to the inside of a pipe and forming a corrosion spot. The removal of the foreign particles, such as the iron compounds or corrosion products, therefore serves the twofold purpose of cleaning the fluid metered at or delivered from the terminals or stations and also removes materials which would initiate further and/or subsequent corrosion or abrasion in the pipe line or in the pipe line equipment.

It should also be pointed out that other treating materials, such as various known corrosion inhibitors, can be injected with the particle-attaching material into the pipeline.

The foregoing disclosure and description of the invention is illustrative and explanatory thereof and various changes in the size, shape and materials, as well as in the details of the illustrated construction, may be made within the

scope of the appended claims without departing from the spirit of the invention.

What is claimed is:

1. The method of removing foreign particles including particles of a size less than 40 micron from petroleum liquid flowing in a section of pipeline and from the interior of the pipeline itself without causing stoppage of flow or pressure drop which comprises the steps of, injecting particulate particle-attaching material which has an attractiveness for the foreign particles in an amount determined by the length of pipe and the concentration of foreign particles at the entrance to the section, and removing the particulate material with the collected foreign particles at the exit of the section.
2. The method as set forth in claim 1, including the step of returning the cleaned liquid to the pipeline.
